UNITED STATES PATENT OFFICE.

DONALD JOHNSON, OF WEST SUPERIOR, WISCONSIN.

DOOR.

SPECIFICATION forming part of Letters Patent No. 437,438, dated September 30, 1890.

Application filed March 12, 1890. Serial No. 343,583. (No model.)

To all whom it may concern:

Be it known that I, DONALD JOHNSON, a citizen of the United States, residing at West Superior, in the county of Douglass and State 5 of Wisconsin, have invented certain new and useful Improvements in Doors; and I do hereby declare the following to be a full, clear, and exact description of the invention, such as will enable others skilled in the art to which it 10 appertains to make and use the same.

My invention consists in a new and improved folding door, which is formed of sections hinged together on vertical lines and suspended at its upper edge, so that the 15 door can be folded back flat against the jamb of the door-casing, thus obviating the necessity of providing a space between the walls for its reception.

My invention will be hereinafter fully described and claimed.

Referring to the accompanying drawings, Figure 1 is a side view showing my new and improved folding door partly opened. Fig. 2 is a top plan view of the door and the track 25 on which it is supported. Fig. 3 is a detail view of one of the swiveled castings which support the door, and Fig. 4 is a detail view of a section of the track on which the said casting runs.

30 The same letters of reference indicate corresponding parts in all the figures.

Referring to the several parts by letter, A indicates the door-frame, which is here shown in connection with my folding door. The top 35 of this frame is formed with the central longitudinal slot B. The door proper is formed in three vertical sections C' C², although it may be formed of any desired number of sections. These sections are hinged at their 40 meeting edges, as shown, and the rear section C² is hinged to the door frame or jamb in the usual manner.

To the top of the door-framing are secured the longitudinal tracks D D, each of which 45 is formed at its inner edge with the longitudinal upwardly-projecting flange D', the tracks being secured at each side of the central slot B, so that their inner-edge flanges project up in the said slot, as shown.

50 On one side of the upper end of each door-section is bolted an angle-plate E, the upper end of which extends over the upper edge of the door, and through this upper part E' of

this angle-plate passes a swivel-bolt F, the upper part of which passes through a runner 55 or casting G. This casting G is formed at each longitudinal side with the downwardly-projecting guide-flanges G' G', which, when the several parts are secured in their operative positions, fit over the upwardly-projecting inner-edge flanges of the track D D. It will thus be seen that the door-sections are supported at their upper ends on the tracks 60 D by the swiveled castings, and when the door is to be opened, it is pushed back, as 65 shown in the drawings, when the flanged castings G will slide freely upon the flanged tracks D, the pivots or swivels F in the upper ends of the door-sections turning freely and easily in the castings G, preventing all 70 possibility of binding. The door thus slides back easily and folds flat against the door-frame, where it is out of way, occupying but little room, and it can be as readily closed again.

75 From the foregoing description, taken in connection with the accompanying drawings, the construction, operation, and advantages of my new and improved folding door will be readily understood.

80 It will be seen that my invention is simple and strong in construction, that the door occupies an extremely small space when folded, and that it can be employed where there is no room for forming a space between the 85 walls for the reception of the old style of sliding door. It can be manufactured at a comparatively small cost and for any size openings, or for single or double doors.

Having thus described my invention, what 90 I claim, and desire to secure by Letters Patent, is—

95 The combination of the door formed of the hinged sections, the angle-plates secured to the upper ends of the said sections, the swivels F, the castings G, formed with the parallel downwardly-extending edge-flanges, and the track-plates having the longitudinal upwardly-extending flanges at their inner edges, substantially as set forth.

100 In testimony whereof I affix my signature in presence of two witnesses.

DONALD JOHNSON.

Witnesses:

H. E. TICKNOR,
R. JOHNSON.
